UNITED STATES PATENT OFFICE.

FRANK W. MARSTON, OF BROCKTON, AND EDMUND E. CLOSE, OF SOUTH HANOVER,
MASSACHUSETTS, ASSIGNORS TO CLOSE MANIFOLD MFG. COMPANY, OF SOUTH
HANOVER, MASSACHUSETTS.

COMBINATION TOOL.

Application filed February 4, 1925. Serial No. 6,699.

This invention relates to a combination tool and more particularly to one which is of especial utility to persons engaged in the motor car repair trade.

5 An object of the invention is to produce, at low cost, a simple and yet efficient tool having a plurality of uses, and which may be knocked down to occupy but little space in a tool kit, or for the purpose of shipping, if desired.

10 A further object of the invention is to closely associate two tools necessary to accomplish certain work and which heretofore were separate devices in such manner that each is aided in its operation by the other, and which may be so associated as to become inseparable under ordinary usage.

15 It is a further object of the invention to so construct the tool that one of its parts in conjunction with another of its parts conveniently and efficiently forms a holder for other tools.

20 The invention further consists in certain features of construction and arrangement which will be fully understood from a description of the drawings and the claims hereinafter given.

25 Of the drawings:

Figure 1 represents a side view of the tool 30 showing a valve grinding tool assembled therewith.

Figure 2 is a view similar to Figure 1 but showing the tool ready for use to unseat a bushing.

35 Figure 3 is a view similar to Figure 2, but partially broken away and showing it in the act of unseating a bushing.

Figure 4 is a side view of the tool in another position in which it is used in seating a bushing.

40 Figure 5 is a section on the line 5—5 Figure 1.

Like characters represent like parts throughout the several figures of the drawing.

45 Referring to the drawing:

The drawing herewith illustrates a simple and inexpensive construction and an arrangement of tool embodying the invention, but it will be understood that changes might be made therein without departing from its spirit and scope.

In the present instance the spindle 10 has a hub like device 11 slidably mounted thereon from which extends a portion 12 arranged to form a holding means or operating handle or lever of such construction as to be valuable for another use to be described.

55 The spindle 10 at its lower end is bifurcated as at 13, the limbs or legs 14 being resilient and normally actuated to spring apart into divergent relation, while at its upper end it is provided with a removable hand piece, normally serving as a stop, shown herein as an enlargement 15, which normally prevents the said spindle from passing through the hub 11 in one direction.

60 Under ordinary usage the bifurcated end of the spindle 10 will be prevented from 70 passing through the hub 11 because of the resistance of the spring legs 14, and therefore it might be said that the hub 11 and its extension 12 and the spindle 10 are normally inseparable.

75 The legs are bored as at 16 to provide a holder for other tools, one of which is shown in Figure 1 of the drawing, such as a valve grinding tool 17, the shank or spindle 18 of which is inserted in the bore 16 and 80 thereafter the hub 11 is forcibly slid along the spring legs 14 causing them to firmly grip the said spindle 18.

85 As seen in said Figure 1, the combined action of the hub 11 and legs 14 conveniently provides a chuck to hold tools of various kinds, while the upper part of the spindle 10 serves as a means to hold the tool to its work by one hand of the operator, and with the other the extension 12 is manipulated to accomplish certain of the work intended for this tool.

90 A set screw 19 is provided which serves to retain the spindle 10 and hub 11 in any given relative position.

95 Another important feature of the invention is its adaptability to a use very commonly required, viz, the removal of bushings from their sockets and their replacement in sockets, each of which operations 100 this tool accomplishes and each of its parts aiding the other in those operations.

Figure 2 shows the tool about to be used to unseat the bushing 20 from the socket of

a sleeve 21 in which instance the portion 12 is used as a handle to guide the spindle 10 to its work and steady the hub 11 when said spindle is being driven through the said hub which will at that time rest on the sleeve 21 as seen in Figure 3, the hand piece 15 being at this time removed from the spindle 10 to allow it to pass through the hub and sleeve.

10 As the spindle is driven toward the bushing 20 the legs 14, acting under their natural tendency to assume a divergent relation, will expand until they meet the wall of the socket, ensuring engagement with the said bushing which upon further driving of the spindle will be forced from its position.

15 Preferably the entrance to the bore 16 will be countersunk as at 25 to thereby provide a more effective contact between the legs 20 14 and the bushing 20.

20 Figure 3 of the drawings shows the relative positions of the parts of the tool, and the action of the legs 14 just before and during engagement thereof with the bushing.

25 To insert a bushing as 26 into a sleeve, the tool is reversed as seen in Figure 4, the spindle 10 at that time becoming the handle by which to guide it, and the extension 12 the effective portion.

30 The bushing 26 will first be positioned in the sleeve 21 preparatory to driving it home, the reduced part 27 of the portion 12 will be directed into the bushing, the shoulder 28 resting thereon, and by tapping the hub 11 on the flattened surface 29 provided thereon, the said bushing will be forced into place and the tool withdrawn.

35 From the foregoing it will be readily seen that the tool has at least three useful purposes and is composed of but three parts including the set screw 19 which however might be dispensed with if desired.

Having described the invention we claim:

40 1. A combination tool comprising a spindle having a bifurcated end providing resilient legs normally actuated to spring apart into divergent relation for the purpose of unseating an object and having a receptacle to receive a tool at said bifurcated end; a hub slidably mounted on said spindle and having a control member extending therefrom, said member comprising a tool arranged to seat an object which the said spindle is arranged to unseat; and being arranged to be slid along said legs whereby they may be caused to grip a tool inserted therebetween, and means to secure said hub

and control member relatively to said spindle.

2. A combination tool comprising two members each of which is arranged to operate on the same object, one to seat the object and the other to unseat it; each of which forms a handle for the other during the operation of the other, one of which is movable relatively to the other, and arranged perpendicularly with respect to each other; one of said members having a bifurcated end providing resilient legs; the other member having a work engaging shoulder thereon; and means to secure one of said members relatively to the other.

3. A combination tool comprising two members arranged perpendicularly to each other, one of said members having a bifurcated end and being arranged to be forced through a hole provided in the other member for the purpose of unseating an object, which member provides a handle for the said first member, the other member being arranged to seat an object and having a blow receiving head and an object engaging shoulder for the purpose of seating an object, the said first member providing a handle for said second member during the operation thereof; and means to secure said members in fixed relative position.

4. A combination tool comprising two members normally in assembled relation and arranged perpendicularly to each other, one of said members having a bifurcated end and being arranged to be forced through a hole in the other member; the other member having a work engaging shoulder thereon and being arranged to be forcibly driven in the direction of its length, said first member providing a handle for said second member.

5. A combination tool comprising two members normally in assembled relation and arranged perpendicularly to each other, one of said members having a bifurcated end and being arranged to be forced through a hole provided in the other member; the other member having a work engaging shoulder thereon and being arranged to be forcibly driven in the direction of its length, said first member providing a handle for said second member; and means to lock said members in a given relative position.

Signed by us at South Hanover, Massachusetts, the 20th day of February, 1926.

EDMUND E. CLOSE.
